UNITED STATES PATENT OFFICE

JOHN KARMAZIN, OF DETROIT, MICHIGAN

RADIATOR CONSTRUCTION

Application filed November 19, 1927. Serial No. 234,333.

This invention relates to heat exchange devices and particularly to that type of heat exchangers for the cooling of a fluid which has become heated by compression or by contact with bodies of higher temperatures such as parts of an internal combustion engine, refrigerating plant or the like or which may be used to reduce the temperature of a surrounding medium by forcing a cooling fluid there-through, and is an improvement on my pending application Serial No. 183,663, filed April 14, 1927.

The principal object of this invention is to provide a heat exchange unit in which a multiple series of heat exchanging tubes are used and which are placed in a staggered relation with respect to each other for the maximum heat transfer effect.

Another object of the invention is to provide an inlet or outlet bracket to be attached to the respective ends of the heat exchange unit by a suitable means such as rivets to withstand high pressures.

It is a still further object of this invention to provide a fin and tube type element for radiator cores in which the tubular projection is substantially elliptical in cross section to permit a stream line surface for more complete contact with the external heat exchange medium.

It is a still further object of this invention to provide a fin and tube type element for heat exchange units in which the tubes will be stream line in shape and in which the inlet and outlet connections may be more permanently attached thereto to permit increase of pressure, better efficiency and greater capacity of the unit.

Further objects and advantages of the invention will appear from the following detailed disclosure thereof together with the attached drawings which illustrate preferred forms of embodiment thereof and, in which,

Figure 1 is a side elevation of a completed core of a heat exchanger adapting the principles of the invention,

Figure 2 is a side elevation of the radiator core shown in Figure 1,

Figure 3 is an enlarged side view of the in-

let or outlet attachment to be used on a triple series radiator,

Figure 4 is a partial side view of a modified form of heat exchanger,

Figure 5 is an end elevation of a double series heat exchange unit similar to that shown in Figures 1 and 4,

Figure 6 is a section on the line 6—6 of Figure 5,

Figure 7 is a partial plan view of the double series core element showing the shape of the tubular projections,

Figure 8 is a diagrammatic view of the effect of the air on the different shapes of tubes.

Figure 9 is a section on line 9—9 of Figure 4,

Figure 10 is a section on line 10—10 of Figure 7.

A radiator or heat exchange unit 10 as shown in Figure 1 is supported in side channel brackets 11 and 12 and is composed of integral fin and tube elements as generally shown and described in detail in my patent Serial No. 1,591,323, patented July 6, 1926. A plurality of these integral fin and tube type elements are cooperatively telescoped in mutual relation and a radiator core heat exchange unit may be fabricated from a sufficient number of these core elements to make the necessary size of unit depending upon specific conditions.

As shown in Fig. 2, a multiple row of these tubular passages are provided and each row is provided with U-shaped connections 13 and 14 at the ends so that a continuous closed circuit is formed from the top of the radiator to the lower part thus providing an elongated continuous path for the fluid to be cooled. At the top and bottom of the radiator unit 90 an inlet and outlet flange 15 which is duplicated in all respects is provided with a series of projections 16 of the number sufficient to correspond with the number of vertical rows of tubular projections in the unit. In other words, as shown in Figure 2, a triple series of tortuous path conduits for the fluid is formed from the triple series of cooperating projections 16 which will be provided with the header 15. At the same time, the three 100

projections 16 will enter into a common channel 15a in the header 15 which in turn will be suitably connected with a pipe thread 17 to the usual connections for the heat exchange unit. For ease in forming, the three projections 16 will be in the same plane and at each end of the radiator the necessary bends in either the outer series of pipes as shown at the top 18, or as in the center channel as in the lower end of the radiator 19 will be made to permit the connection of the header 15 thereto.

The channels 11 and 12 may be provided with a semi-circular opening 20 and are of a generally triangular shape frame to permit the adaptation of this heat exchange to the mechanism for which it is adapted. The main body of the core however is preferably rectangular in shape and only the ends of the frame are triangular and offset at the bottom to more effectively support the unit. It is also obvious that a top U-shaped channel 21 may be provided to further strengthen the unit and to aid it in support.

The construction of this form of the device will be apparent. The multiplicity of vertical rows of tubular projections are interconnected and although the connections as shown in Figure 2 in which each vertical row comprises a single tortuous path is desirable it is obvious that there are many other arrangements of connections of the individual tubular conduits in order that the introduced fluid may pass a sufficient distance through the projections so that the heat exchange may be most effective. To make the tubular projections in a complete circuit the U-shaped projections or yokes are introduced between the adjacent ends of different tubes.

A slightly modified form of construction is shown in Figures 4 to 6 in which but a double series of projections is shown. Here again the course of a fluid introduced is in a vertical plane from top to bottom of the radiator and again the projections 25 are staggered from the line of projections 26 in order that the most effective cooling may be brought about. Here again as in the previous form, U-shaped channel members 27 are used to support the ends of the heat exchange unit and the internal construction of the core is of the fin and integral tube type as before mentioned. For the purpose of introducing and removing the fluid, inlet and outlet connections are used as more particularly shown in Figure 6. In general, they comprise an enlarged member 28 provided with short inner tubes 29 and 30 which may have a flange to securely fit the member 28 and which will project into several of the fin elements to reinforce the connection. A suitable flange 31 permits the use of rivets 32 to attach the inlet or outlet connections to the channel bracket 27 to permit the use of higher pressures. A pipe thread or other

suitable connecting means 33 is provided for external attachment to the fluid source.

It will be noted that in this multiple series of radiator tubes together with the simple inlet and outlet bracket 28 it is possible to introduce the fluid to be cooled at one end of the radiator and to permit its discharge at the other end thereof. The interior course is divided, part of it being sent through one row of the radiator and the other portion of the fluid being sent through the other course. The staggered effect of the tubes permits adequate cooling and thus the capacity of this core unit is substantially greater than that provided by a single unit. It has been found that when but one series of elements was used and there was only one tortuous path, or when the tubular projections were not staggered, a part of the cooling air would pass through the radiator without coming in contact with the heat exchanger. It is practically impossible however in the present form for any cooling medium to pass through without coming in contact with some one of the tubular projections of the integral fins which are necessarily at the same temperature and also effectively aid in the heat transfer.

Figures 9 and 10 illustrate particular features of the telescoping elements 42 which are provided with central reinforcing fins 42a in which central perforations 42b are made. These central reinforcing members also divide each stream of fluid in the conduits and remove the heat from the central portion thereof. As these members 42a are also integral with the remainder of the strip, it is also clear that the heat exchange is materially increased by their area. The perforations 42b permit the solder to run through rather than collect and be wasted as heretofore. These perforations 42b are best shown in the enlarged section in Figure 10 which also shows the one piece construction of the strip elements which may have either the circular or oval projections stamped thereon.

Another feature of the invention resides in the fact that due to the manner of connecting the tubular or oval conduits, the entrapped fluid whose heat value is to be carried, is forced to flow, not only from end to end of the heat exchanger but also must flow from top to bottom thereby materially increasing the length of its path and its cooling or heating contact area. The slightly increased cost of construction is overcome by the greatly increased efficiency and the compact arrangement requires but very little more space for an element twice the size of the usual construction. It is to be particularly noted that the fin and tube type construction is that particularly described in applicant's prior patent heretofore mentioned and that the elements are readily adapted to have a plurality of rows of pro-

jections stamped at once thereupon. This construction, however, is the subject matter of a separate application. This construction has been found to be materially cheaper, 5 more efficient and generally more desirable than the previously known separate tube and fin type of radiator.

It has also been found that the elliptical construction of the projections or tube, 40, 10 on the element or fin 42, will permit a much greater cooling rate inasmuch as the cooling air more completely contacts with the surface of the tubular projections. As shown in Figure 7 the tubes are substantially egg shaped or elliptical and thus stream line and as noted in Figure 8, the percentage of surface of the projections which is effected by the cooling air of other cooling medium is much greater with this shape of projection 15 than is possible with the normal circular projection. The increase in capacity due to these oval projections also permits a smaller radiator core for the same capacity and the amount of air or other cooling medium which 20 may be efficiently drawn through the tubes can be greatly increased because of this increase in heat exchange rate. With such projections it is desirable to reinforce them by the cross members 44 and it is possible to 25 stamp these projections in the same manner and with similar machinery as the normal and heretofore used circular projections.

It is to be particularly noted that the multiple series radiator particularly uses the 30 egg shaped or elliptical projections or tube inasmuch as the amount of air which can be drawn through the radiator to efficiently exchange the heat which under normal conditions would not be practical with the circular 35 projections or tube, is highly satisfactory, and the amount of cooling can be greatly increased. It will also be noted that in order to permit the use of the elliptical projections near the end of the radiator to permit attachment of either the U-shaped yokes or the 40 connection of the inlet or outlet connections, it will be necessary to remove the central cross members 44 so that the projections will not be interfered with.

45 The foregoing constructions represent an improvement in radiator construction and is a considerable improvement in the structures shown in my prior patent and particularly in the means to increase the efficiency and capacity of the radiator units by means of using a plurality or multiple series of tortuous path circuits for the fluid to be cooled or heated and in which the use of positively 50 attached inlet and outlet brackets such as shown in Figure 3 and shown to embrace rivets as shown in Figure 6 will permit the increase in pressures. The multiple series of vertical rows of elliptical or stream line projections will also permit a much greater 55

amount of cooling with a smaller expenditure of energy to draw the cooling medium such as air through the radiator.

While I have illustrated several forms of embodiment of the invention, I am aware 70 that many modifications are possible and I therefore desire protection on the invention within the scope and spirit of the disclosure thereof and as more particularly claimed in claims appended hereto. 75

I claim:

1. In a radiator of the class described, a plurality of sheet metal core elements having integral tubular projections oval in cross section extending transversely therefrom, said 80 elements being assembled with the tubular projections of adjacent elements in telescoping relation, and having the maximum cooling surface relative to the surface of the radiator.

2. In a radiator of the class described, a 85 fin and tube type core element having a plurality of integral fin and tubular projections thereon in which the tubular projection is of a stream line substantially oval shape in cross section, and having the maximum cooling 90 surface relative to the core surface.

3. A radiator of the class described, a plurality of fin and tube type core elements having tubular projections assembled in cooperating relation and means to connect said tubular projections to provide a multiple series of tortuous paths for the cooling fluid flow and means to introduce the cooling fluid into at least two series of tortuous paths. 95

4. In a heating radiator of the class described, a plurality of tubular, parallel spaced passages in staggered relation said passages being stream line in cross section, heat radiating fins in contact with walls of said tubular passages and means for connecting said tubular passages to form a plurality of continuous conduits and means to introduce and remove a cooling fluid from at least two of said parallel passages. 100

5. A heating unit comprising a plurality 110 of superposed fin and tube type core elements having spaced parallel tubular projections in staggered relation extending transversely from one side thereof, the tubular projections of one element being 115 adapted to nest within the tubular projections of the juxtaposed element to form a plurality of continuous conduits a frame for said core and means to externally connect a fluid source to said core by attachment to 120 said frame.

6. A heating unit core and supports therefor; comprising a plurality of superposed fin elements having tubular projections in spaced relation extending transversely from 125 one end thereof, the tubular projections of one element being adapted to nest within the tubular projections of the juxtaposed element to form a plurality of continuous conduits and means to externally connect a fluid 130

source to said conduits, said means for attaching the external connections to the core being further attached to the support to permit the use of high pressure.

- 5 7. A heating unit core and support therefor; comprising a plurality of superposed fin elements having integral tubular projections in spaced, staggered relation extending transversely from one end thereof, the tubular projections of one element being adapted 70 to nest within the tubular projections of the juxtaposed element to form a plurality of continuous conduits, means to externally connect a fluid source to said conduits, said 75 10 means for attaching the external connections to the core being further attached to the support to permit the use of high pressure, said projections being substantially elliptical in transverse cross section.
- 20 8. A heating unit comprising a plurality of superposed fin elements having integral projections thereon, said projections forming closed conduits from end to end of the unit, means to connect said conduits to form 80 25 at least two separate continuous conduits through the heating unit, the said elements being provided with fins integral with said projections, said projections being staggered 85 in relation one to another in order to permit 90 30 contact with the greatest amount of cooling air possible.

9. A heating unit comprising a plurality of superposed fin elements, said elements being provided with integral projections and 95 35 intermediate reinforcing members there across to form closed conduits, a frame for supporting said unit, and outlets attached to said frame ends and telescoping with the tubular projections to permit the use of high 100 pressure.

10. A heating unit of the class described having a supporting frame comprising a plurality of conduits in spaced parallel relation, said conduits being externally connected to provide a plurality of tortuous 105 paths extending from end to end of the radiator and from top to bottom thereof, said conduits being provided with inlet and outlet means secured to said frame to provide at 110 50 least two sets of tortuous paths, the outlet and inlet means being attached to and telescoped within the conduits to withstand high pressures, and central reinforcing means in said conduits to additionally divide the 115 55 stream in each conduit to remove the central hot or cold region.

11. In a heat exchanger of the class described comprising a plurality of fin and integral tubular projections superposed to 120 60 form a plurality of closed conduits, the conduits being in staggered relation and oval in shape to permit the maximum cooling surface relative to the surface of the heat exchanger, and means to introduce high pressure fluid into said conduits.

12. In a heat exchanger of the class described comprising a plurality of superposed elements, each element being provided with a plurality of integral oval projections, the central part of which has a transverse reinforcing member which removes the heat from the central part of the stream, the superposed elements forming a plurality of spaced staggered conduits, means to connect these conduits in a plurality of tortuous paths extending throughout the radiator, and means to introduce high pressure fluid into 70 75 said conduits.

13. In a heat exchanger of the class described comprising a plurality of superposed elements, each element being provided with integral oval projections in staggered relation, the central part of which has a transverse member additionally removing heat from a fluid stream in the center thereof, the superposed elements forming a plurality of spaced staggered conduits, means to support the heat unit including a frame, means to connect the conduits into a plurality of tortuous paths extending throughout the radiator 80 85 90 and additional means mounted on the frame to introduce high pressure fluid into said conduits.

14. A heat exchange unit or radiator comprising a plurality of conduits, said conduits being connected in a multiplicity of separate fluid paths extending from side to side of the radiator and from end to end thereof, the paths being in staggered relation to permit the maximum cooling thereof, a frame to support said conduits, and inlet and outlet connections for the radiator, the connections being riveted to the frame to withstand high pressure.

15. In a heat exchanger of the class described, comprising a plurality of fin and integral tubular projections superposed to form a plurality of closed conduits, means to introduce high pressure fluid into said conduits, said means including an enlarged member adapted to be connected to an external source provided with a plurality of apertures, and short tubes projecting therefrom telescoping with said conduits to reinforce the connection therewith.

16. In a heat exchanger of the class described, comprising a plurality of fin and integral tubular projections oval in shape superposed to form a plurality of closed conduits, means to introduce high pressure fluid into said conduits, said means including an enlarged member adapted to be connected to an external source provided with a plurality of apertures, and short tubes projecting therefrom telescoping with said conduits to reinforce said connection.

In testimony whereof I have affixed my signature to this specification.
